DESIGN FOR A CROCHETED LADY'S HANDBAG

Lilly Kertész Rotkel, New York, N. Y.

Application May 28, 1943, Serial No. 110,321

Term of patent 7 years

To all whom it may concern:

Be it known that I, Lilly Kertész Rotkel, a citizen of Hungary, residing at New York, New York, in the county of New York and State of New York, have invented a new, original, and ornamental Design for a Crocheted Lady's Handbag, of which the following is a full, clear and exact description, reference being had to the accompanying drawing, forming a part thereof,

In the drawing:

Fig. 1 is a front elevational view of a crocheted lady's handbag, showing my new design.

Fig. 2 is a rear perspective view of the same.

I claim:

The ornamental design for a crocheted lady's handbag, as shown.

LILLY KERTÉSZ ROTKEL.
